United States Patent Office

Des. 197,575
Patented Feb. 25, 1964

197,575

COVER FOR A CASSEROLE OR SIMILAR ARTICLE

Gerald D. Gulotta, New York, N.Y., assignor to Owens-Illinois Glass Company, Toledo, Ohio, a corporation of Ohio

Filed July 15, 1963, Ser. No. 75,797

Term of patent 14 years

(Cl. D44—15)

FIG. 1

I claim:

The ornamental design for a cover for a casserole or similar article, as shown.
